The ornamental design for a control unit for medical and surgical fluid delivery device, as shown and described.

DESCRIPTION

FIG. 1 is a perspective view of a control unit for medical and surgical fluid delivery device showing our new design;

FIG. 2 is a plan view of the angled front control panel thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.

FIG. 1
